UNITED STATES PATENT OFFICE.

WILLIAM STEELE, OF ALLEGHENY, PENNSYLVANIA.

DESIGN FOR A BUTTON OR BADGE.

SPECIFICATION forming part of Design No. 28,057, dated December 21, 1897.

Application filed April 8, 1897. Serial No. 631,027. Term of patent 34 years.

To all whom it may concern:

Be it known that I, WILLIAM STEELE, a citizen of the United States, residing in Allegheny, in the county of Allegheny and State 5 of Pennsylvania, have invented a new and original Design for Buttons or Badges; and I do hereby declare the following to be a full, clear, and exact description thereof, reference being had to the accompanying drawings, in 10 which—

Figure 1 is a plan view of my design, on an enlarged scale. Fig. 2 is an edge or side view thereof, showing it applied to a button; and Fig. 3 is a cross-section thereof.

15 The drawings show my design as applied to a button or badge provided with a square body portion.

The leading features of my design consist in a button or badge having a square body 20 portion and having on its top surface a rep-

resentation of a block-house provided with a door, sloping roof, and port-holes. A row of beads are placed around the outer edge of the top surface of the button or badge.

A represents the square body portion of the 25 button or badge; B, the top surface of the body portion, and C the block-house, having the door D, the sloping roof E, and the port-holes F. Upon the top surface and around the outer surface of the body portion A are a number 30 of raised beads G.

What I claim is—

The design for a button or badge, substantially as herein shown and described.

In testimony whereof I have hereunto set 35 my hand.

WILLIAM STEELE.
